UNITED STATES PATENT OFFICE

104,138

DESIGN FOR A COMBINED FRUIT AND VEGETABLE EXPRESSER AND STRAINER

Domenick A. Grandinetti, Syracuse, N. Y.

Application September 25, 1936, Serial No. 65,005

Term of patent 14 years

To all to whom it may concern:

Be it known that I, Domenick A. Grandinetti, a citizen of the United States, residing at 1101 Court Street, in the city of Syracuse and in the county of Onondaga, and State of New York, have invented a new, original, and ornamental Design for a Combined Fruit and Vegetable Expresser and Strainer, of which the following is a specification, reference being had to the accompanying drawing, forming part thereof, wherein

Fig. 1 is a front elevational view of the combined expresser and strainer showing my new design.

Fig. 2 is a side elevational view thereof.

Fig. 3 is a top plan view thereof.

I claim:

The ornamental design for a combined fruit and vegetable expresser and strainer, as shown.

DOMENICK A. GRANDINETTI.
